Pyam L. Pendleton, Pawtucket, R. I., assignor to
 Pantex Pressing Machine, Inc., Pawtucket,
 R. I., a corporation of Delaware

Application September 1, 1930. Serial No. 479,121

6 Claims. (Cl. 68—9)

This invention relates to a garment pressing machine adapted to be used by tailors, drycleaners, clothing manufacturers and others for steaming, pressing and shaping trousers, coats, 5 vests, skirts and other articles of wearing apparel and involves the use of cooperative pressing elements, one of which, commonly known as the head, is hinged to swing about a horizontal axis parallel with the longitudinal center and some distance to the rear of the other pressing 10 element technically known as the buck so that when the press head is opened a clear open space will be afforded across the upper surface and around the marginal edges of the buck to facilitate the placing of the garments thereon preparatory to pressing.

In machines of this character it is a common practice to operate the press head from its open to its closed position by fluid-pressure-operated 20 motors or other power mechanism to be returned to its open position by counter-weights or equivalent retracting means.

It is obvious, however, that when operated through its pressure stroke by power more or less 25 beyond the control of the operator there is always present the liability of introducing the hands or arms of the operator between the pressing elements either from necessity in straightening out the garments on the buck or through carelessness on the part of the operator.

For this reason various devices have heretofore been provided requiring the use of both hands of the operator in the control of the power to the motor or some part of the connections between the motor and press head to reduce the danger 35 factor to a minimum.

These so-called two-hand controls are necessarily complicated and add materially to the cost of the machine and the main object of the present invention is to avoid the use of these two-handed power control systems by necessitating the hand operation of the press head from its open to its closed position before the power can be applied and thereby to further reduce the liability of accident to the operator during such movement by making it practically impossible to operate the press head to its pressing position by power until it is closed or at least sufficiently closed to prevent any possibility of getting any 45 part of the fingers, hand or arms of the operator between the pressing elements when the power is applied.

In other words I have sought to provide simple and efficient power-operated means for exerting pressure upon the head toward the buck only

after said head has been moved by hand to its closed position.

One of the specific objects is to provide a normally open or broken mechanical linkage between the power unit and press head controlled entirely by the movement of the press head from its open to its closed position so that the linkage between the power unit and press head will not be completed until the press head is brought substantially to its closed position at which time the 60 operation of the power unit will be optional with the operator.

Other objects and uses relating to specific parts of the machine will be brought out in the following description.

In the drawings:

Figure 1 is a side elevation of a garment pressing machine embodying the various features of my invention, the press head and operating means therefor being shown by full lines in their normal 70 open positions and by dotted lines in their closed positions.

Figure 2 is a similar side elevation of the same machine showing the press head and operating means therefor in their closed positions.

Figure 3 is an enlarged detail sectional view taken in the plane of line 3—3, Figure 2.

Figure 4 is an enlarged detail sectional view taken in the plane of line 4—4, Figure 1.

Figure 5 is a horizontal sectional view taken 85 along the line 5—5, Figure 4.

Figure 6 is a detail sectional view taken in the plane of line 6—6, Figure 5.

As illustrated this machine comprises a frame 90 —1— having a work table —2— and pedestals —3— and —3'— projecting upwardly above the work table for receiving and supporting a lower pressing element or buck —4—, and a rocker arm —5— carrying an upper pressing element or head —6—.

The buck —4— and press head —6— may be heated by any well-known means and one or both of these pressing elements may be provided with means commonly employed in machines of this type for supplying steam to the article under 100 pressure for rendering the same pliable preparatory to pressing, shaping and drying said article but, in view of the fact that the means for heating and also the means for introducing steam into the garment forms no part of my present invention, it is not necessary to further illustrate or describe the construction of the buck or press head.

The rocker arm —5— constitutes a lever of the first order in that it is fulcrumed or pivoted 110

at —7— intermediate its ends to the pedestal —3— to swing about an axis parallel with the longitudinal center of the buck and some distance to the rear thereof to leave a clear open space entirely around the marginal edges of the buck for the proper manipulation and positioning of the work thereon, the head —6— being mounted upon the front end of the rocker arm —5— to move about the axis of the pivot —7— into and out of 10 pressing co-action with the buck —4—.

The rear end of the rocker arm —5— is provided with a counter-weight —8— adapted to counter-balance the weight of the head —6— to normally hold the latter in its open position, said 15 counter-weight —8— being provided with a recess —9— opening from the lower side thereof for receiving a portion of a relatively small lever —10— and a coil spring —11—, the lever —10— being pivoted at its forward end at —12— to the 20 rocker arm —5— and extended rearwardly across the recess —9— for engagement with the lower end of the spring —11— having its upper end engaged with the top wall of the recess, the rear end of the lever —10— being held by the spring 25 —11— against a limiting stop —13— on the lower side of the rear end of the rocker arm —5— as shown in Figure 1.

The intermediate portion of the lever —10— is pivotally connected to the upper end of a 30 longitudinally extensible toggle link —14— having its lower end pivotally connected at —15— to the upper end of another toggle link —16— which has its lower end pivotally connected at —17— to the lower rear portion of the frame —1—. 35 The links —14— and —16— with their pivotal connection —15— constitute a toggle connection between the frame and rear end of the rocker arm —5— through the medium of the lever —10—, which, together with the spring —11—, 40 forms a resilient connection between the toggle and rocker arm —5— to relieve the press head from excessive shock when brought into pressing co-action with the buck and also to compensate for varying thicknesses of the articles operated 45 upon.

That is, if the press head should be brought into pressing co-action with the buck before the toggle members —14— and —16— are straightened, said toggle could have a further straightening movement against the action of the spring —11— through its connection with the lever —10—.

The intermediate portion of the lower toggle link —16— is pivotally connected by a link —18— 55 to the rear end of what may be termed a semi-floating lever —19— which is pivoted intermediate its ends at —20— to a power operated lever —21— and has its forward end provided with a roller —22— movable into and out of engagement 60 with a latch or detent —23— in a manner and for a purpose presently described.

The power operated lever —21— extends forwardly and rearwardly beyond its pivotal connection —20— with the semi-floating lever —19— 65 and has its rear end pivoted at —24— to the frame of the machine and its front end pivotally connected at —25— to a yoke —26— which is mounted on the upper end of a piston rod —27— of a fluid-pressure-operated motor —28—, the 70 latter being mounted upon the lower front portion of the frame of the machine.

The latch —23— is arranged in an upright position in approximately the vertical plane of the semi-floating lever —19— and has its lower end 75 pivoted at —29— to a vertically adjustable link

—30— and its upper end provided with a rearwardly projecting shoulder or fulcrum member —23'— adapted to be engaged by the forward end —22— of the semi-floating lever —19— when the latter has been rocked about its pivot —20— to 80 a predetermined position by the closing of the head —6— upon the buck —4—.

That is, the linkage between the power lever —21— and press head —6— is arranged in such manner that when the press head is fully opened, 85 the front end of the semi-floating lever —19— will be some distance above and at the rear of the shoulder —23'— on the latch —23— and when the press head is closed, by means of a coil spring —31— which is interposed between the rear edge 90 of the latch —23— and front portion of the frame —1— for normally urging the upper end of the latch rearwardly and permitting said latch to yield forwardly when engaged by the front end 95 —22— of the semi-floating lever —19—.

The latch lever —23— is yieldingly held in position to automatically engage the front end 100 —22— of the semi-floating lever —19— when the press head is closed, by means of a coil spring —31— which is interposed between the rear edge 105 of the latch —23— and front portion of the frame —1— for normally urging the upper end of the latch rearwardly and permitting said latch to yield forwardly when engaged by the front end 110 —22— of the semi-floating lever —19—.

The supporting member —30— for the latch 115 —23— is pivoted at —32— to the front portion of the frame —1— and has its rear end connected by a bolt —33— to an underlying bracket —34— on the frame whereby the member —30— and latch may be adjusted vertically to bring its shoulder —23'— into proper position for interlocking engagement with the front end —22— of the semi-floating lever —19— when the press head —6— is brought to its pressing position.

Suitable means is provided for withdrawing the latch lever —23— from its operative position and for this purpose a hand lever —35— of the bell crank type is pivoted at —36— to a portion of the frame —1— and has its forwardly projecting arm 120 provided with a handle —35'— and its other arm provided with a link —37— having a slotted portion —37'— adapted to receive a pin —38— on the upper end of the latch —23— above the shoulder —23'— so that the lifting of the front end of the lever —35— will cause the rear wall of the slotted portion —37'— of the link —37— to withdraw the latch —23— out of the path of movement of the front end —22— of the semi-floating lever —19—.

When the latch is withdrawn in the manner just described it is evident that the press head —6— may be closed and opened by hand without in any way affecting the operation of the power lever —21— and it is equally evident that the 135 power lever —21— may be operated by the motor —28— without in any way affecting the operation of the press head.

It is also obvious that when the hand lever —35— is restored to its normal position to permit the latch lever —23— to assume its operative position the press head —6— may be moved from its open position to substantially its closed position and vice versa without engaging the front end —22— of the semi-floating lever —19— with 140 the latch shoulder —23'— and that under these conditions the power lever —21— may be operated by the motor without in any way affecting the operation of the press head.

In other words power from the motor —28— 145

can not be applied to move the press head from its extreme open position to its closed position and the motor only becomes effective when the press head is closed by hand, at which time the 5 front end —22— of the semi-floating lever —19— will be brought into locking engagement with the shoulder —23— of the latch —23—.

When the press head is thus closed by hand to bring the front end —22— of the semi-floating 10 lever —19— into engagement with the latch shoulder —23— the motor —28— may be operated to raise the front end of the power lever —21— about its pivot —24—, thereby rocking the rear end of the semi-floating lever —19— upwardly about the fulcrum connection between the lever —19— and latch —23— for additionally straightening the toggle members —14— and —16— through the medium of the link —18— and incidentally exerting pressure of the press 15 head upon the article on the buck —4—, Figure 2.

When the press head —6— is moved by hand from its extreme open position to substantially its closed position the toggle members —14— and 20 —16— will approximate a straightened position, although slightly flexed inwardly as shown by dotted lines in Figure 1, at which time the front end —22— of the lever —19— will be in operative position to engage the shoulder —23— 25 of the latch —23— ready for the operation of the motor —28— upon the lever —21— for completing the closing movement of the press head upon the work and straightening the toggle members —14— and —16— to lock the press head in its 30 pressing position until released by the operation of the lever —35— either by hand or automatically in a manner presently described, for withdrawing the latch —23— from its operative position.

40 The means for automatically tripping the latch or detent —23— includes an upright bell-crank-lever —40— pivoted at —41— to the front portion of the frame —1—, some distance below the hand lever —35— and having its upper arm 45 adapted to engage the rear edge of the pendent arm of the hand lever —35—, the lower arm of the lever —40— being provided with a roller —42— adapted to be engaged by the rear arm of an operating lever —43— which is pivoted at 50 —44— to the yoke —26— on the piston rod —27— and has its forward end weighted to normally hold the same against an underlying limiting stop —45— on the yoke —26—.

When the piston rod —27— and yoke —26— 55 are in their normal or extreme down positions the rear end of the lever —43— will underlie the lower end —42— of the lever —40— so that when the press head —6— is closed by hand and the front end —22— of the lever —19— is

60 brought into operative engagement with the shoulder —23— of the latch —23— and power is applied to the motor —28— the upward movement of the piston rod —27— and its yoke —26— will cause the rear end of the lever —43— to engage the lower end —42— of the lever —40—, thereby rocking said lever —43— against the action of its counter-weight —44— until the lower end of the lever —43— passes upwardly beyond the roller —42— at which time the press 65 head —6— will have been forced into pressing engagement with the work upon the buck —4—.

When the motive power for the motor —28— is cut off the piston rod —27— will automatically descend by its own weight aided by that of the 70 front end of the lever —21—, thereby causing the rear end of the tripping lever —43— to engage the roller —42— and force the lower end of the lever —40— rearwardly which will cause the upper end of the lever to rock the lower arm of the bell-crank-lever —35— and link —37— in 75 the same direction for tripping the latch —23— from engagement with the front end —22— of the lever —19—.

As previously stated, when the press head —6— is closed upon the work by the operation of the motor —28— the toggle members —14— and —16— will assume a straightened position, thereby locking the press head in its closed position and it therefore becomes necessary to provide some means for flexing the toggle inwardly from its straightened position before the press head 80 can be raised.

For this latter purpose, a releasing lever —46— is pivoted at its rear end at —47— to the frame —1— to extend forwardly therefrom directly over the intermediate portion of the lever —21— to play between a pair of limiting stops —48—, said release lever —46— being spring pressed into engagement with the lower stop —48— by means of a coiled-spring —50—.

It therefore follows that when the front end of the lever —21— is raised by the upward movement of the piston rod —27— of the motor —28—, the intermediate portion of the lever —21— will engage and raise the front end of the release lever —46— against the action of the spring —50—, thus causing the spring —50— to exert downward pressure upon the lever —21—.

This downward spring pressure upon the lever —21— is arranged to continue until after the latch —23— has been withdrawn from engagement with the front end of the lever —19— by the operation of the tripping lever —43— against the lower end of the lever —40— and resultant operation of the levers —35— and link —37— 110 to trip the latch —23—, these latter operations being caused by the downward movement of the piston rod —27— of the motor —28— after the press head has performed its pressing operation upon the work, at which time the downward pressure of the lever —46— upon the lever —21— will be transmitted through the pivot —20— to the lever —19—, thereby allowing the rear weighted end of the lever —19— to rock about the pivot —20— and through the medium of the link —18—, to flex the toggle members —14— and —16— forwardly a sufficient distance to enable the counter-weight —8— to continue the automatic opening movement of the press head to its extreme open position as shown in Figure 1, it 125 being understood that the rear end of the lever —19— is provided with extra weight —19'— to effect this initial automatic opening movement of the press head.

Motor control

135

The motor —28— is preferably of the fluid pressure piston type comprising an upright cylinder —28— and a hollow piston —51— having a piston rod —27— connected thereto as shown 140 more clearly in Figure 4, said cylinder being provided with a suitable gland —52— in which the piston —51— is movable.

The cylinder —28— is provided with a suitable piston chamber —53— open at the top for receiving the piston —51— and has its lower end provided with an inlet chamber —54—, an outlet chamber —55— and a heating chamber —56—, the inlet chamber being connected by a pipe —57— to any suitable source of supply for steam 145 150

or other fluid under pressure while the outlet chamber —55— discharges through a pipe —58— to the atmosphere or to any waste reservoir, not shown.

5 The heating chamber —56— communicates with the inlet chamber —54— below the lower end of the piston —51—, as shown more clearly in Figure 6, and is provided with a drainage pipe —59— connected to the waste pipe —58— 10 through the medium of a trap —60— having adjustable means as —61— for opening and closing communication between the heating chamber —56— and waste pipe —58—.

15 The steam receiving chamber —54— is connected to the lower end of the piston chamber —53— by means of a port —62— which is controlled by a self-closing valve —63—, spring 20 pressed against its seat by coil spring —64— in the direction of flow of steam, said valve being mounted upon a stem —65— which extends to the exterior of the base of the cylinder —28'— to be opened against the action of the spring —64— in a manner hereinafter described.

25 The lower end of the piston chamber —53— is also connected by a port —66— to the exhaust chamber —55—, said port being controlled by a self-closing valve —67— which is normally held against its seat by coil spring —68—, the valve being provided with a stem —69— extending to the exterior of the base of the cylinder to be opened against the action of the spring in a manner presently described.

30 These valves —63— and —67— operate independently of each other and for this purpose a pair of bell-crank-levers —70— and —70'— are pivoted respectively at —71— and —71'— to opposite sides of the cylinder —28'— to extend downwardly therefrom across and closely adjacent the outer ends of the valve stems —65— and 40 —69— respectively.

45 Each bell-crank-lever is connected by a link —72— to one end of a hand lever —73— which is pivotally mounted upon the frame of the machine below the table —2— near the front edge thereof for convenience of operation as shown in Figures 1 and 2 in which but one of the links —72— and its operating lever —73— are shown for operating the valve —63—, it being understood that a similar link —72— and hand lever —73— are to be used for opening the valve —67—.

50 The lower end of the piston rod —27— is connected to the lower end of the piston by means of a ball and socket joint —74— to compensate for slight inaccuracies in the axial alignment of the piston and rod, the upper end of said rod being screw threaded and engaged in a threaded socket in the lower end of the yoke —26— to enable the yoke and the piston to be relatively adjusted as may be required to produce the desired timing of the operation of the levers —21— and —19—.

Operation

65 Assuming that the various moving parts of the machine are in their normal positions with the press head in its extreme open position as shown in Figure 1 and that it is desired to press a garment or other article which has been previously spread out upon the buck —4—, the operator will first move the press head together with the rock 70 arm —5— forwardly and downwardly by means of the handle —a— to substantially its closed position as shown by dotted lines in Figure 1, thereby causing the toggle members —14— and —16— to flex rearwardly to an approximately but not 75 quite straightened position.

This rearward flexing movement of the toggle members —14— and —16— causes the semi-floating lever —19— to be rocked about the pivot —20— from the position shown by full lines to the position shown by dotted lines in Figure 1, 80 during which movement the front end —22— of the lever —19— will engage the upper end of the latch —23— and force the same forwardly against the action of the spring —31— until the front end —22— of the lever —19— is registered with the lower face of the latch shoulder —23'—, thus permitting the spring —31— to force the latch into engagement with the end —22— of the lever.

85 Then, if it is desired to use the power of the motor —28— for exerting additional pressure of the press head upon the garment on the buck —4—, it is simply necessary to open the valve —63— through the medium of its corresponding hand lever —73—, link —72— and bell-crank-lever —70—, thereby permitting the steam to flow from the source of supply through the pipe —57— into the receiving chamber —54— and thence through the open port —62— into the cylinder —53—, for forcing the piston —51— and yoke —26— upwardly.

90 This upward movement of the piston —51— and yoke —26— causes a similar upward rocking lifting movement of the lever —21— about its pivot —24—. The front end of the semi-floating lever —19— is then in engagement with the shoulder —23'— of the latch —23— so that the upward rocking movement of the lever —21— causes a similar upward movement of the lever —19— about the fulcrum connection between the front end of the lever —19— and latch shoulder 105 —23'— which effects the straightening and locking of the toggle members —14— and —16— through the medium of the link —18— which, it will be observed upon reference to Figures 1 and 2, forms a toggle connection with the link 110 —19— and when the toggle members —14— and —16— are straightened and locked the toggle members —18— and —19— will also be straightened and locked to assist in holding the press head in its pressing position until the valve —63— 115 is closed by the release of its corresponding operating lever —73—.

120 During this upward movement of the piston —51— the rear end of the lever —43— will be free to ride loosely across the lower end of the lever —40— and at the same time the lever —21— will be placed under more or less downward spring pressure through the medium of the lever —46— and spring —50—.

125 When the pressing operation is completed, the steam inlet valve —63— controlling the port —62— will be closed automatically by the spring —64— immediately upon the release of the corresponding lever —73—, whereupon the other lever —73— controlling the exhaust valve —67— 130 will be opened to allow the steam to escape from the lower end of the piston through the then open port —66— and thence outwardly through the waste pipe —58—.

135 During this exhaust of the steam from the cylinder, the piston —51— will descend by its own weight aided by the pressure of the spring —50— through the medium of the lever —46—, thereby causing the toggle members —19— and —18— to flex downwardly aided by the weight 140 —19'— on the rear end of the lever —19— and effecting a corresponding forward flexing of the toggle members —14— and —16—, which forward flexing movement is continued by the counter-weight —8— on the rear end of the head 145 150

supporting arm —5— for raising the press head to its extreme open position as shown by full lines in Figure 1.

During this downward movement of the piston 5 —51— and resultant opening of the press head, or just before the press head reaches its open position, the rear end of the tripping lever —43— will engage the lower end of the lever —40— and rock the same rearwardly, thereby causing 10 the upper end of the lever —40— to operate the hand lever —35— and link —37— to withdraw the latch —23— from engagement with the front end of the lever —19—, thus permitting said lever to assume its normal position, shown by 15 full lines in Figure 1, and completing the cycle of operation in that all the moving parts will then be restored to their normal or starting positions.

It is evident, however, that the latch —23— may be tripped from its holding position at any 20 time by simply operating the lever —35— and link —37— to the position shown by dotted lines in Figure 2.

It will be observed that when the press head is brought to its closed position by the operator 25 the momentum imparted to the toggle members —18— and —19— by the upward movement of the weight —19— causes said members and also the toggle members —14— and —16— to straighten, thereby placing the spring —11— 30 under compression after the head —6— is actually closed upon the buck, and it is during this straightening of both toggles and incidental compression of the spring —11— that the front end —22— of the lever is caused to engage and 35 interlock with the latch —23— ready for the operation of the power device for exerting extra pressure upon the head through the medium of the member —21— and both of the toggles.

When the detent latch —23— is tripped either 40 by the operation of the hand lever —35— or by the operation of the lever —40— upon the return of the power device, the weight —19— will flex the toggle members —18— and —19— aided by the expansion of the spring —11— sufficiently 45 to slightly flex the toggle members —14— and —16— aided by the expansion of the preferably compressed spring —11—, whereupon the weight —8— on the rear end of the head-supporting lever —5— will automatically return the head to its 50 open position.

The construction and operation described is particularly simple and efficient in that it renders such operation safe in the hands of inexperienced or careless users in that the press can not be 55 closed by power until the press head is substantially closed by hand, but obviously various changes might be made in the detail construction without departing from the spirit of the invention as defined in the following claims.

60 What I claim is:—

1. In a garment pressing machine, a frame, a buck mounted on the frame, a rocker arm pivotally mounted on the frame to swing about a horizontal axis located some distance to the rear 65 of the buck and parallel with the longitudinal center thereof and extending forwardly and rearwardly from its pivot, a press head mounted on the front end of the rocker arm to move therewith into and out of pressing co-action with the buck, 70 a toggle connection between the rear end of the rocker arm and frame, said press head and rocker arm being movable by hand from its extreme open position to an approximately closed position, the toggle being arranged to assume an 75 approximately straight position when the press

head is approximately closed, a piston motor having its piston operable in one direction by fluid under pressure, a lever pivoted to the frame and operatively connected to said piston to be rocked thereby about its pivot, a second toggle having one of its members pivoted to said lever and its other member connected to one of the first-named toggle members, a fulcrum member at one side of the pivotal connection between said lever and second-named toggle member and arranged to be engaged by said toggle member only when the press head approximates its closed position, said second-named toggle member being actuated by the lever about said fulcrum member to straighten the second named toggle and simultaneously to straighten the first-named toggle to close the head during a power stroke of the piston.

2. In a garment pressing machine, a frame, a buck mounted on the frame, a rocker arm fulcrumed on the frame to extend forwardly and rearwardly therefrom and movable about an axis substantially parallel with the longitudinal center and some distance to the rear of the buck, a press head mounted on the front end of the 100 rocker arm to move therewith into and out of pressing co-action with the buck, a toggle connection between the frame and rear end of the rocker arm, a lever pivoted to the frame, a second toggle connection between said lever and first-named toggle and having one of its members extended beyond its connection with the lever, said toggles being flexed by the opening movement of the press head and moved toward a straightened position by the closing movement 110 of the press head, a bearing member for engaging the extension of the second-named toggle member as the press head approaches its closed position, and power-operated means for rocking said lever and thereby moving the extension of 115 the second named toggle into engagement with said bearing member for simultaneously straightening both toggles to effect the complete closing of the head.

3. In a garment press, a buck, a self-opening 120 press-head adapted to be closed at will, a fulcrum bearing, a lever, means actuated by the closing movement of the press head for moving said lever into engagement with said bearing, motor-actuated means for rocking said lever about said 125 bearing, to exert final closing pressure upon the press head, and means for moving said bearing out of engagement with said lever.

4. In a garment press, a frame, a buck, a self-opening press-head adapted to be closed at will, 130 a bearing member, a toggle connection between the frame and press-head, a lever fulcrumed on the frame, a second lever pivotally mounted on the first lever, means actuated by the straightening of the toggle for rocking said second lever 135 into engagement with said bearing member, and motor means for operating the first lever to cause the lever to rock about said bearing member as a fulcrum for additionally straightening the toggle.

5. In a garment press, a frame, a buck, a self-opening press-head adapted to be closed at will, 140 a lever of the third kind normally disengaged from its fulcrum, means actuated by the closing movement of the press-head for engaging said lever with its fulcrum and for transmitting motion from the lever to the press-head when the lever is rocked about said fulcrum, means for rocking said lever about the fulcrum for exerting final closing pressure upon the press-head, and 145

means for disengaging the fulcrum and lever to allow the press-head to open.

6. In a garment press, a frame, a buck, a self-opening press-head adapted to be closed at will, 5 a lever of the second kind fulcrumed upon the frame, a lever of the third kind pivotally mounted on the first named lever and normally disengaged from its fulcrum, means actuated by the press head when closing for causing the second named

lever to engage its fulcrum and for transmitting motion from said second named lever to the press head, means for rocking the first named lever about its fulcrum for exerting extra closing pressure upon the press head, and means for disengaging the second named lever from its fulcrum to allow the press-head to open.
